UNITED STATES PATENT OFFICE

JOSEPH S. STRING, OF EAST ORANGE, NEW JERSEY, ASSIGNOR TO J. S. & J. F. STRING INCORPORATED, OF NEWARK, NEW JERSEY, A CORPORATION OF CONNECTICUT

OIL BURNER

Application filed August 6, 1926. Serial No. 127,515.

This invention relates to hydrocarbon burners in which the fuel is exteriorly atomized by means of any expansive fluid such as air or steam.

5 The principal object of the invention is the production of a hydrocarbon burner of the type specified which shall be easily manufactured and easily assembled and disassembled whereby repair or replacement of any 10 single part may be quickly effected.

A further object of the invention is the production of a hydrocarbon burner of the above type having a construction permitting the flare or spread of the atomized fuel to be 15 varied without changing the volume or pressure of the expansive fluid.

A further object of the invention is the production of a burner which may be constructed entirely from bars and plates of 20 standard size thereby lessening the cost of manufacture.

A further object of the invention is the production of a hydrocarbon burner having a construction permitting the fuel tube or passageway to be vertically and bodily adjusted 25 to vary the space between its discharge end and the discharge end of the expansive fluid tube or passageway.

Further and other objects and advantages 30 of the invention will appear from the subjoined description, the invention consisting in the novel burner and parts and combinations thereof hereinafter more particularly described and then specified in the claims.

35 In the accompanying drawing illustrating a practical embodiment of the invention:

Fig. 1 is a section taken through the burner.

Fig. 2 is a front elevation thereof.

40 Fig. 3 is a bottom plan view of the forward end of the expansive fluid tube in spaced relation to the fuel tube.

Fig. 4 is a perspective view of the forward end of the fuel tube.

Fig. 5 is a section on the line 5—5 of Fig. 1.

45 Fig. 6 is a perspective view of the bearing for the lip forming the end of the expansive fluid tube.

Referring in detail to the several figures of the drawing:

50 1 indicates the side plates of the burner

which are connected together by the bolts 2 passing through the upper wall 3 comprising a bar, the parts being tied together by means of the nuts 4. 5 indicates a squared fuel tube having an inclined interior passageway 6 55 therein extending to the forward end of the tube and communicating with a horizontal passageway 7 at the rear end of the tube. Said rear end of the tube is reduced in size as shown and is adapted to be connected in 60 any manner to a pipe or other means communicating with a source of fuel supply such as oil. As indicated, the passageway 6 is inclined downwardly from the forward end of the fuel tube 5 so that when the fuel supply is 65 shut off any fuel remaining in the passageway will flow rearwardly and back into the source of supply.

The forward wall of the tube 5 is inclined as at 8 and as illustrated in Fig. 4 and is 70 provided with side flanges 9 removably receiving therebetween a cap or head 10 which is secured to said tube by the screw 11. The head 10 is provided with an inclined slot 12 terminating in a horizontal slot 13, said slots 75 forming with the inclined wall 8 and flanges 9 a fuel-receiving chamber communicating with the fuel passageway 6. Extending through the base of the cap or head 10 and communicating with the horizontal slot 13 80 are a plurality of spaced perforations 14 providing outlets for the fuel after it has flowed from the passageway 6 and into the chamber formed by the slots 12 and 13.

The fuel tube 5 is provided with a recess 85 15 therein, the upper wall of which is slotted and receives the shank of a screw 16 which is screwed through the wall 3. The head of the screw 16 lies within the recess 15. This arrangement not only permits the tube 5 to be moved horizontally but to be raised bodily vertically to and away from the wall 3 by manipulation of the screw 16 90 in an obvious manner. As shown in Fig. 1 said tube 5 is in its lowermost vertical position and is shown resting on a supporting block 17 having an inclined face 18, said supporting block being detachably secured to both side plates 1 by suitable screws 19.

20 indicates a squared atomizing fluid tube 100

through which the atomizing fluid, such as air or steam, passes to atomize the fuel flowing from the perforations 14. The forward end of said tube is rounded as at 21 and is 5 slidably received by a head comprising a bearing 22 having an inclined face 23 provided with projecting horns 24. The forward end 21 of the tube is cut in a plane inclined to the horizontal axis of the tube 10 whereby when said end is in fully advanced position its upper surface will be flush with the surface of the inclined face 23. By cutting the end of said tube in the manner described a lip 24' having a rounded end is 15 provided on the outer end thereof which is adapted to project intermediate the horns 24 and adjacent the perforations 14. The position of the tube 20 is inclined as respects that of the tube 5 and is such that the inclined face 23 is parallel or substantially parallel to the base of the tube 5 when the parts are properly assembled with said tube 20 slidably engaging the inclined face 18 of the block 17. The rear end of the tube 20 25 is adapted to be connected to any source of expansive fluid supply such as air or steam.

25 indicates a supporting block which is detachably fastened to the side plates 1 by suitable screws 26. Said supporting block 30 supports the bearing or head 22 and is provided with a pin 27 extending upwardly into a suitable aperture 28 in said bearing to prevent movement thereof. 29 indicates a block detachably screwed to the side plates 1 by 35 suitable screws and acting as a support on which the tube 20 is slidable. Said block 29 has a screw-threaded bolt 30 passing therethrough carrying a nut 31 fastened thereon and also provided with the usual head 32. 40 The forward end of said bolt threads through a block 33 which is secured by screws 34 to the lower side of the tube 20. Because of the connections and structure described, when the nut 32 is rotated the tube 45 20 will be moved bodily on the supporting block 29 to vary the position of the lip 24' in the bearing 22 and intermediate the horns 24 in an obvious manner.

When the fuel such as oil is forced 50 through the tube 5 it flows into the chamber formed by the slots 12 and 13 and through the perforations 14 whereupon it is atomized by the expansive fluid such as air which is forced through the tube 20. It is 55 then ignited by any suitable flame (not shown) as ordinarily in burners of this type. The spread or flare of the atomized fuel may be varied in an obvious manner without changing the air pressure or volume of air 60 passing through the tube 20 by merely shortening or lengthening the effective length of the lip 24' by manipulation of the nut 32. The horns 24 are provided to guide the air flowing through the tube 20 by confining it between two side walls. 65

In some cases it will be found desirable in order to secure the best results to adjust the horizontal position of the tube 5 by moving it forwardly or rearwardly on the block 17. Furthermore, if a flame of greater thickness is desired, this may be secured by raising the tube 5 vertically by means of the adjusting screw 17 whereby a larger space will obtain between the under side of the tube 5 and the outlet opening in the forward end 21 of the tube 20. The cap or head 10 is made removable for purposes of cleaning and the tubes, plates and bars are all of standard shape which are machined to the proper size and dimensions, thus making for 70 cheapness and ease of manufacture. Furthermore, the parts are detachably held together thus facilitating the repair of the burner or replacement of any of its parts should they become defective or broken. 75

What I claim as my invention is:

1. A hydrocarbon burner provided with a fuel tube and an atomizing fluid tube adapted to discharge fluid for atomizing the fuel discharged from said fuel tube and means for adjusting the relative positions of said tubes to vary the flare or spread of the atomized fuel while keeping constant the amount of fluid discharged from the atomizing fluid tube and means for varying the thickness 90 of the atomized fuel.

2. A hydrocarbon burner provided with a fuel tube having an outlet opening in its forward end, an atomizing fluid tube lying inclined towards the said fuel tube and having the discharge end thereof cut at an angle to the axis of said atomizing fluid tube to produce an inclined face lying substantially parallel to the base of said fuel tube, said discharge end normally lying adjacent said outlet opening. 100

3. A hydrocarbon burner provided with a fuel tube having a discharge opening therein, an atomizing fluid tube provided with an outlet opening lying adjacent said discharge opening when the parts are in operative position and a stationary bearing slidably receiving the forward end of said atomizing fluid tube, said end being movable therein and into proximity with the discharge opening 110 in said fuel tube.

4. A hydrocarbon burner comprising two side plates, a wall connected thereto, a fuel tube slidably horizontally intermediate said side plates, means for varying the position of said fuel tube in a vertical plane, and an atomizing fluid tube slidably intermediate said side plates towards and from said fuel tube. 120

5. A hydrocarbon burner provided with a fuel tube and an atomizing fluid tube inclined towards said fuel tube with the discharge end thereof cut at an angle to its axis and its edge lying in a substantially horizontal plane and means adjacent the discharge 125 130

end of said atomizing fluid tube to vary the flare or spread of the fuel discharged from said fuel tube.

6. A hydrocarbon burner provided with a fuel tube and an atomizing fluid tube slidable with respect to said fuel tube and in atomizing relation thereto and provided with a lip at its discharge end and a bearing through which said discharge end of said atomizing fluid tube is movable, said bearing being provided with extending horns thereon for receiving said lip therebetween.

7. A hydrocarbon burner comprising two side plates, a wall connected thereto, a fuel tube movable intermediate said side plates and provided with a recess therein, a screw extending through said wall and provided with a head received by said recess and an atomizing fluid tube movable between said side plates and towards and from said fuel tube and in atomizing relation thereto.

8. A hydrocarbon burner comprising a supporting structure, a fuel tube held thereon, a block, a bearing on said block, means connecting said bearing and block and an atomizing fluid tube having its discharge end supported by said bearing and slidable therein towards and from said fuel tube and in atomizing relation thereto.

30 9. A hydrocarbon burner comprising a fuel tube, a bearing, an atomizing fluid tube in atomizing relation to said fuel tube and having its discharge end slidable in said bearing and a screw-threaded bolt engaging said 35 atomizing fluid tube for varying the position of said end in said bearing.

40 10. A hydrocarbon burner comprising a fuel tube, a bearing, an atomizing fluid tube in atomizing relation to said fuel tube and having its discharge end slidable in said bearing, a block supporting said atomizing fluid tube, a second block secured to said second-named tube and a bolt extending through said blocks for varying the position of the 45 discharge end of said tube in said bearing.

Signed at East Orange, in the county of Essex and State of New Jersey, this 3rd day of August, A. D. 1926.

JOSEPH S. STRING.
